UNITED STATES PATENT OFFICE.

PHILIP H. GERHARD, OF AUSTIN, TEXAS.

APPARATUS FOR TREATING TIMBER.

SPECIFICATION forming part of Letters Patent No. 794,605, dated July 11, 1905.

Application filed January 26, 1905. Serial No. 242,770.

To all whom it may concern:

Be it known that I, PHILIP H. GERHARD, a citizen of the United States, residing at Austin, in the county of Travis and State of Texas, have invented certain new and useful Improvements in Apparatus for Treating Timber; and I do declare the following to be a full, clear, and exact description of the invention, such as will enable others skilled in the art to which it appertains to make and use the same.

My invention relates to improvements in apparatuses for the treatment of timber and other material; and it consists in certain novel features of construction, combination, and arrangement of parts hereinafter described and claimed.

The object of my invention is to provide a simple, inexpensive, durable, and efficient apparatus by means of which railroad cross-ties, fence-posts, and the like may be expeditiously and economically treated by immersion in a bath of some preserving liquid.

The above and other objects, which will appear as the nature of my invention is better understood, are accomplished by the construction illustrated in the accompanying drawings, in which—

Figure 1 is a perspective view of an apparatus constructed in accordance with my invention. Fig. 2 is a vertical longitudinal sectional view through a slightly-modified form of the apparatus, and Fig. 3 is a vertical transverse sectional view taken on the line 3 3 in Fig. 2.

Referring more particularly to Fig. 1 of the drawings, the numeral 1 denotes a container for the liquid preserver with which the beams of timber or other material are to be treated. As shown, this receptacle or container is in the form of a rectangular tank or vat, which has its forward end inclined, as shown at 2, to permit the timbers to be readily introduced into the liquid preserver without splashing the same. At the opposite or rear end of the tank

1 is an endless elevator 3, by means of which the timbers are removed from the tank, drained, and deposited in a pile or stack. As shown, this endless conveyer is in the form of a pair of sprocket-chains 4, passed around sprocket-wheels 5, which are secured adjacent

to the ends of upper and lower shafts 6 and 7, journaled in bearings 8 upon the front side or section 9 of an inverted-V-shaped frame 10. The opposite side or section 11 of the frame 10 is inclined in a reverse direction to the side 55 or section 9, and each of said sides or sections consists of two side beams 12, connected by cross-beams 13. The lower pair of sprocket-wheels 5 are located adjacent to the rear end of the tank 1, so that the timbers or other objects treated in the latter may be readily lifted upon said chain and engaged with fingers 14, provided at suitable intervals upon its links. The upper pair of sprocket-wheels 5 are disposed adjacent to the upper end of the frame 60 10, so that the conveyer discharges the timbers upon the downwardly-inclined side or section 11 of the frame, which forms a chute or skid. In order to catch and save the preserving liquid which drips from the timbers 65 10, so that the conveyer discharges the timbers upon the downwardly-inclined side or section 11 of the frame, which forms a chute or skid. In order to catch and save the preserving liquid which drips from the timbers 70 10, so that the conveyer discharges the timbers upon the downwardly-inclined side or section 11 of the frame, which forms a chute or skid. In order to catch and save the preserving liquid which drips from the timbers 75 10, so that the conveyer discharges the timbers upon the downwardly-inclined side or section 11 of the frame, which forms a chute or skid. In order to catch and save the preserving liquid which drips from the timbers 80 10, so that the conveyer discharges the timbers upon the downwardly-inclined side or section 11 of the frame, which forms a chute or skid. In order to catch and save the preserving liquid which drips from the timbers 85 10, so that the conveyer discharges the timbers upon the downwardly-inclined side or section 11 of the frame, which forms a chute or skid. In order to catch and save the preserving liquid which drips from the timbers 90 10, so that the conveyer discharges the timbers upon the downwardly-inclined side or section 11 of the frame, which forms a chute or skid. In order to catch and save the preserving liquid which drips from the timbers 95 10, so that the conveyer discharges the timbers upon the downwardly-inclined side or section 11 of the frame, which forms a chute or skid. In order to catch and save the preserving liquid which drips from the timbers 100 10, so that the conveyer discharges the timbers upon the downwardly-inclined side or section 11 of the frame, which forms a chute or skid.

The elevator may be driven in any desired manner; but I preferably provide upon the shaft 7 a gear 18, which meshes with a pinion 19 upon a shaft 20, journaled in bearings upon the lower portion of the frame-section 9. Upon said shaft 20 is secured a band-wheel or pulley 21, which may be driven by any suitable motor. In the drawings I have shown said pulley 21 connected by a belt 22 to a pulley or belt-wheel 23 upon the crank-shaft of the steam-engine 24. The latter is mounted upon the side of an upright steam-boiler 25, which is located adjacent to the frame 10. The usual steam connections are provided between the steam-space of the boiler and the steam-chest of the engine-cylinder.

The preserving liquid within the tank 1 may be heated in any desired manner; but I preferably provide a steam-coil or other steam-heating device 26 in the bottom of the said tank and connect it by the steam-pipe 27 with the steam-space of the boiler 25, as shown.

In Figs. 2 and 3 of the drawings I have shown a slightly-modified form of the apparatus, the frame 10 having its side sections 9 and 11 pivotally connected at their upper 5 ends, as shown at 30, so that they may be folded upon each other, and the lower end of the frame-section 9 having its side bars 12 detachably pivoted, as shown at 31, to the tank 1. This construction permits the frame 10 to be readily removed from the tank 1 or folded over upon the same, so as to facilitate 10 transportation of the apparatus. It also permits the lower ends of the endless elevator-chains to extend beneath the level of the liquid 15 in the tank 1, so that the timbers or other objects may be readily floated into engagement with the fingers 14 upon said chains. In order to hold the frame-sections 9 and 11 in their open position, any suitable means may be provided. As shown in the drawings, I have pivoted bars 32 upon the side beams 12 of the frame-section 9, as shown at 33, and detachably connect them with the side bars of the frame-section 11, as shown at 34.

25 The construction, operation, and advantages of my improved apparatus will be readily understood from the foregoing description, taken in connection with the accompanying drawings. It will be seen that after the timbers or other objects have been treated in the tank 1 they are elevated by the endless chains 30 and then deposited in a pile or stack at the lower end of the frame-section 11. The preserving liquid which drips from the timbers 35 as they are elevated falls down into the drip

pan or receptacle 15 and returns to the tank. The drip-pan 15 (shown in Figs. 2 and 3) is preferably detachably connected, as shown at 35, and its lower open end discharges the liquid falling thereon into the tank 1.

40 Various changes in the form, proportion, and the minor details of construction may be resorted to without departing from the principle or sacrificing any of the advantages of this invention.

45 Having thus described my invention, what I claim as new, and desire to secure by Letters Patent, is—

Apparatus for treating timber, comprising a receptacle for the treatment of wood by immersion in a liquid preservative, a frame having upwardly-inclined outwardly-converging sides, one of which rises from within the said receptacle, an endless traveling elevator on the said side of the said frame, means to cause said 50 endless traveling elevator to move so that its outer lead moves upwardly, and a drip-pan under the said side of the frame to return the drippings from the wood to the said receptacle while the wood is being raised by the 55 said elevator, the latter discharging the wood to the other side of the said frame, substantially as described.

In testimony whereof I have hereunto set my hand in presence of two subscribing witnesses.

PHILIP H. GERHARD.
